UNITED STATES PATENT OFFICE.

HEINRICH THEODOR NESZLER, OF CHEMNITZ, SAXONY, ASSIGNOR TO FRANZ PRETZEL & CO., OF BERLIN, GERMANY.

APPARATUS FOR THROWING BELTS OVER THEIR PULLEYS.

SPECIFICATION forming part of Letters Patent No. 429,861, dated June 10, 1890.

Application filed January 22, 1890. Serial No. 337,760. (No model.) Patented in Germany December 28, 1886, No. 40,567, and May 12, 1889, No. 50,199; in Belgium October 10, 1888, No. 83,653; in England December 18, 1888, No. 18,489; in France June 3, 1889, No. 198,695; in Norway June 3, 1889, No. 1,382; in Luxemburg June 3, 1889, No. 9,141; in Austria-Hungary June 3, 1889, No. 26,095 and No. 47,036; in Italy June 7, 1889, No. 25,572; in Denmark June 17, 1889, No. 1,275, and in Switzerland June 25, 1889, No. 1,111.

To all whom it may concern:

Be it known that I, HEINRICH THEODOR NESZLER, a subject of the King of Saxony, and a resident of Chemnitz, in the Kingdom of Saxony, German Empire, have invented certain new and useful Improvements in Apparatus for Throwing Belts Over Their Pulleys, (for which Letters Patent have been granted in Germany, No. 40,567, dated December 28, 1886, and No. 50,199, dated May 12, 1889; in England, No. 18,489, dated December 18, 1888; in Denmark, No. 1,275, dated June 17, 1889, and in France, No. 198,695, dated June 3, 1889, under name of Franz Pretzel; in Belgium, No. 83,653, dated October 10, 1888; in Norway, No. 1,382, dated June 3, 1889; in Italy, No. 25,572, dated June 7, 1889; in Austria-Hungary, No. 26,095 and No. 47,036, dated June 3, 1889; in Luxemburg, No. 9,141, dated June 3, 1889, and in Switzerland, No. 1,111, dated June 25, 1889, under name of Franz Pretzel & Co.,) of which the following is an exact description.

My invention consists of two metallic bars curved to the same radius and one sliding on or in the other. The bars may be flat and provided with slits, or they may be tubular and the one sliding in the other.

In order to make my invention more clear, I refer to the accompanying drawings, in which similar letters denote similar parts throughout the several views.

Figure 1 shows an end view of the apparatus. Fig. 2 shows a side elevation with the arm at its longest reach. Figs. 3 and 4 show the manner of picking up the belt. Figs. 5 and 6 show how the same is placed on its pulleys. Fig. 7 shows an arrangement where the arcs are tubular and slide one within the other.

The apparatus consists of two curved bars *a*, having slits running their whole length and held at the required distance from each other at their upper ends by the cross-piece *b*, while their lower ends are attached to the handle *g*. The cross-piece *b* has two pivots extending outward—one on each side—and on each pivot

a washer *i*. The distance between the outside of bar *a* and inside of washer *i* forms the guide for the second pair of curved bars *m*, 50 which are held at the required distance apart and rigidly connected to each other by means of the cross-pieces *k* and *l*. The cross-piece *l* slides in the slit in bars *a*, while cross-piece *k* is bored through the middle for the reception of steel spindle *n*, having on its outer end the head *p*. The spindle is adjustable in cross-piece *k* by means of the set-screw in Fig. 1. The socket *s*, with disk *r*, is movable on the spindle *n*, and is under pressure of spring *c*, 60 so that it can be accommodated to belts of any breadth and will always be slightly pressed against the one side of the same.

In order to throw a belt over its pulley with this apparatus, it is necessary first to adjust 65 the spindle *n* in its bearing *k*, so that the distance between head *p* and disk *r* shall be about the width of the belt. The spindle is then placed under the belt, as shown in Fig. 3. The head *p* of the spindle must then be 70 brought against the opposite side of the pulley, as shown in Fig. 4, when the spring *c* will be compressed. On raising the apparatus or moving it in the direction of rotation of the pulley the belt on being taken round with the 75 pulley will draw the two parts of the apparatus out of each other as far as necessary, and thus the belt will be laid over its pulley, while the operator may stand still, only having to hold the handle of the apparatus. 80

I can also make the arcs *m* and *a* tubular, as shown in Fig. 7, instead of flat and having guide-slits, which simplifies the construction.

Having thus fully described and ascertained the nature of my said invention, what I desire 85 to secure by Letters Patent of the United States is—

1. In apparatus for throwing belts over their pulleys, the combination of two metallic arcs curved to the same radius and the one sliding 90 in the other, one arc having at its end a spindle for reception of the belt, and the other having its one end rigidly attached to handle *g*, in the manner specified.

2. The combination of the curved bars *a a*,
having slits running their whole length, and
cross-piece *b*, and rigidly attached to handle
g, with the curved bars *m m*, guided in bars
a a, having slits, cross-pieces *b l*, and cross-
piece *k*, with adjustable spindle *n*, head *p*,
disk, and spring *c*, in the manner specified.

In witness whereof I have hereunto set my
hand in presence of two witnesses.

HEINRICH THEODOR NESZLER.
